The ornamental design for a combined electrical wire holder
and test probe guide, as shown and described.

DESCRIPTION

FIG. 1 is a perspective view showing the top, front and left
side of a combined electrical wire holder and test probe
guide which forms my invention;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.
